Primary Examiner — Derrick Holland(74) *Attorney, Agent, or Firm* — Haynes Beffel & Wolfeld LLP; James F. Hann; Andrew L. Dunlap(57) **CLAIM**

The ornamental design for a wire cover for solar panel, as shown and described.

DESCRIPTION

FIG. 1 is a top, front, left side perspective view of a wire cover for solar panel showing my new design;

FIG. 2 is a top plan view thereof;

FIG. 3 is a front elevation view thereof;

FIG. 4 is a right side elevation view thereof;

FIG. 5 is a left side elevation view thereof;

FIG. 6 is a rear elevation view thereof; and,

FIG. 7 is a bottom plan view thereof.

The broken lines shown illustrate environmental structure and form no part of the claimed design.

1 Claim, 3 Drawing Sheets(56)
